UNITED STATES PATENT OFFICE.

TOM C. GRAHAM, OF ALBANY, NEW YORK, ASSIGNOR TO THE EMBOSSED COMPANY,
OF ALBANY, NEW YORK, A CORPORATION OF NEW YORK.

DESIGN FOR A DOMINO.

Application filed June 9, 1928. Serial No. 27,058. Term of patent 14 years.

To all whom it may concern:

Be it known that I, TOM C. GRAHAM, a citizen of the United States of America, residing at Albany, in the county of Albany and State of New York, have invented a new, original, and ornamental Design for Dominoes, of which the following is a specification, reference being had to the accompanying drawing, forming a part thereof.

In the drawing, Fig. 1 is a plan view of the domino, showing my new design, and Fig. 2 is a longitudinal section on the line 2—2 of Fig. 1.

I claim:

The ornamental design for a domino, as shown.

TOM C. GRAHAM.
